F. E. BEST

EXTENSION CYLINDER LOCK

Filed Nov. 29, 1924

Patented Nov. 30, 1926.

1,609,050

UNITED STATES PATENT OFFICE.

FRANK ELLISON BEST, OF SEATTLE, WASHINGTON.

EXTENSION CYLINDER LOCK.

Application filed November 29, 1924. Serial No. 752,918.

My invention relates to improvements in extension cylinder locks and the object of my invention is to improve and simplify the construction of locks of this nature and 5 to render the same more easy to install and adjust and more efficient in operation.

Another object is to provide a lock of this nature in which the extension member has two tubes rigidly secured thereto and 10 arranged to project telescopically into tubular recesses in a lock receiving member and in which two screws entering from the front end of the lock receiving member are threaded into said tubes for relative adjustment of the lock receiving member and the extension member, said tubes projecting outwardly from the end of said extension member and serving as means for securing an externally threaded disc to the end of said 15 extension member, the ends of the screws within the tubes being expanded to prevent complete separation of the extension member and the lock receiving member.

Other objects are to provide means for 20 preventing the extension member from rotating on the lock receiving member, to provide separable face plate means for the lock receiving member, said face plate means being arranged to cover the adjusting screws and to provide armor means for preventing 25 access to the adjusting screws by drilling.

Other and more specific objects will be apparent from the following description taken in connection with the accompanying 30 drawings.

In the drawings Figure 1 is a longitudinal sectional view substantially on a broken line 1—1 of Figure 2 of an extension cylinder lock constructed in accordance with this invention.

Figure 2 is a view partly in section and partly in elevation of the same substantially on broken line 2—2 of Fig. 1.

Figure 3 is a sectional view substantially on broken line 3—3 of Figure 1 except that the lock receiving member and the extension member are shown telescoped to their minimum length and a lock core is shown within the lock receiving member.

Figure 4 is a detached end view looking down into the extension member.

Referring to the drawings, throughout which like reference numerals designate like parts, 5 designates a lock receiving member 55 that is adapted to telescope into an extension member 6. The periphery of the lock re-

ceiving member 5 is provided with longitudinally extending alternate grooves 7 and ridges 8 that interfit with corresponding grooves 9 and ridges 10 in the extension member 6 and prevent relative rotation of said two members. The lock receiving member is provided with an opening 11 of figure 8 cross sectional shape for the reception of a lock core 12 which has a rotatable key 60 plug 13 and which has a locking gate 14 operated by the use of a key in the lock and arranged to engage behind a shoulder 15 in the lock receiving member to prevent removal of the lock core. 70

The lock receiving member 5 is provided at the sides of the figure 8 shaped opening 11 with two tubular bores 16 for the reception of tubes 17 that are rigid with the extension member 6. The tubes 17 are externally provided with conical flanges 18 that seat in countersunk holes in the end of extension member 6 and said tubes 17 extend outwardly from the end of the extension member 6 through an externally threaded 80 disc 20 and are expanded at their outer ends as at 21 to secure the disc 20 to the extension member. 75

Adjusting screws 22 are inserted from the outer end of the lock receiving member into 85 the tubular bores 16 and screw into tubes 17 to adjustably secure the lock receiving member and the extension member together, said screws having heads 23 that seat within suitable counterbores in the contracted outer 90 ends of bores 16 and having their ends expanded as at 24 within the tubes 17 to prevent them from being entirely withdrawn.

The heads of the screws 22 are covered by a drill resistant armor plate 25 of hardened 95 metal that is disposed within a shallow counterbore in the outer end of the lock receiving member.

The outer end of the lock receiving member 5 is provided with expanded sections 100 26 beneath which inwardly bent sections 27 on a face plate 28 are arranged to engage. The expanded sections 26 and inwardly bent sections 27 are each preferably arranged at intervals around lock receiving member 6 105 and face plate 28 respectively so that face plate 28 may be applied by fitting sections 27 over the end of the lock receiving member and then turning the face plate to cause the sections 27 to engage beneath expanded sections 26. The construction of this face 110 plate locking feature is more clearly illus-

trated and described in my copending application Serial No. 749,853, filed Nov. 14, 1924. The face plate 28 is provided with a hole of substantially figure 8 shape for the reception of the figure 8 shaped lock core, the lock core preventing the face plate from being turned when it is inserted.

The face plate 28 fits within an escutcheon plate 30 and bears against a washer 31 that 10 seats upon a flange 32 at the bottom of the escutcheon plate. The washer 31 fits the lock receiving member closely but the opening in the escutcheon plate 30 is large enough so that said escutcheon plate may be passed 15 over the extension member 6.

The key plug 13 in lock core 12 has two longitudinally extending holes 33 for slidably and telescopically receiving two pins 34 that are rigid with a disc 35. The disc 20 member 20 on the end of extension member 6 has a hole extending therethrough that is counterbored on the inner side to afford a shoulder 36 and that has an annular groove 37 in the counterbored portion. A bushing 38 is rotatably disposed in the hole in disc member 20 and has a head 39 arranged to fit against shoulder 36. A throw bar 40 is secured to bushing 38 by rivets 41 and serves in the usual manner to operate a latch.

30 The disc 35 is arranged to fit rotatably in the counterbore in disc member 20 and has a peripherally disposed expansion ring 42 that is arranged to snap into groove 37 to releasably secure the disc 35 to disc member 20. Pins 43 on the end of disc 35 are arranged to operatively engage with bushing 38 for turning the same when the disc 35 is rotated.

40 The disc member 20 that is rigid with the end of extension member 6 is arranged to screw into a latch housing 44 and is locked against rotation in said latch housing by a ball 45 that is operatively disposed in a recess 46 in the side of disc 20 and arranged 45 to be forced outwardly by rotation of a cam member 47 into a groove 48 in latch housing 44. The cam member 47 has an eccentric groove 50 in which ball 45 is operatively disposed and said cam 47 is rotatably mounted in disc 20 and has a transverse groove 51 in its upper end for the reception of a screw driver blade which may be inserted through lock receiving member 5 when the lock core 12 is removed to turn said cam member 47.

55 In the installation of this device the extension cylinder comprising disc 20 extension member 6 and lock receiving member 5 is inserted through a previously prepared opening in a door 52 and made fast to the 60 latch housing 44 which is mortised into the door, by screwing disc 20 into the latch housing. After the disc 20 is properly adjusted in the latch housing it is locked in place by forcing ball 45 outwardly into 65 groove 48. The screws 22 may then be ad-

justed to draw the lock receiving member down snugly onto the escutcheon plate 30. After this has been done the armor plate 25 may be applied, the face plate 28 placed on the end of lock receiving member 5 and 70 rotated to lock the same in place and to properly align the figure 8 hole in the face plate with the figure 8 hole in the lock and the lock core may then be inserted and locked in place thereby making it impossible 75 to turn the face plate and preventing any person except one who has the proper key for removing the lock core from gaining access to the heads of screws 22 or to the cam 47 that locks the extension cylinder 80 against rotation in the latch housing.

The foregoing description and accompanying drawings clearly disclose a preferred embodiment of my invention but it will be understood that this disclosure is merely 85 illustrative and that such changes in the invention may be made as are within the scope and spirit of the following claims.

I claim:

1. In an extension cylinder lock, a lock receiving member having longitudinally extending bores, an extension member, relatively rigid tubes in said extension member arranged to fit slidably within said bores and screws threaded into said tubes and adjustably connecting said lock receiving member and said extension member. 90

2. In an extension cylinder lock, a lock receiving member having two longitudinally extending bores, an extension member arranged to telescope over said lock receiving member, two rigid tubes in said extension member arranged to fit slidably within said bores and adjusting screws in said lock receiving member threaded into said tubes. 100

3. In an extension cylinder lock, a lock receiving member having longitudinally extending bores therein, an extension member slidably thereon, tubes rigid within said extension member and arranged to fit slidably 110 within said bores, screws having their heads countersunk into the end of said lock receiving member and arranged to extend through said bores and screw into said tubes and face plate means arranged to cover the 115 heads of said screws.

4. In an extension cylinder lock, a lock receiving member, having longitudinally extending bores therein, an extension member 120 slidable on said lock receiving member, rigid tubes within said extension member arranged to fit slidably within said bores, screws threaded into said tubes and extending through said bores and having heads that are countersunk in the outer end of said lock receiving member, an armor plate of hardened metal covering the heads of said screws and a face plate covering said armor plate. 125

5. In an extension cylinder lock, two rela- 130

tively adjustable telescopic members, screws connecting said two telescopic members and having heads disposed at the outer end of the outer telescopic member, an armor plate

5 overlying the heads of said screws and a face plate arranged to be placed over said armor plate.

6. In a lock, a lock receiving member, screws having heads disposed at, and operable from the outer end of said lock receiving member for securing the same to another member, an armor plate overlying the heads of said screws and a face plate fitting over said armor plate.

15 7. In an extension cylinder lock a lock receiving member having a receptacle and provided with two longitudinally extending bores, an extension member slideable thereon, two rigid tubes in said extension member arranged to telescope within said bores, screws having their heads embedded in the outer end of said lock receiving member and extending through said bores and threaded into said tubes, an armor plate covering the heads of said screws, a face plate covering said armor plate and arranged to be made fast to said lock receiving member by placing the same thereon and turning, a lock

core arranged to fit within said receptacle, said lock core preventing turning of said 30 face plate, and throw means arranged to be operated by said lock core.

8. In an extension cylinder lock an extension member, an externally threaded disc on the end of said extension member and tubes 35 extending through said disc and into said extension member and serving as a means for securing said disc and said extension member together.

9. In an extension cylinder lock an extension member, a lock receiving member arranged to telescope into said extension member and having two bores extending lengthwise thereof, an externally threaded disc on the end of said extension member, two tubes 45 extending through said disc and through the bottom of said extension member and fitting telescopically into said bores said tubes having flanges abutting against the inner side of the end wall of said extension 50 member and having their outer ends expanded to secure said disc to said extension member, and adjusting screws extending through said lock receiving member and threaded into said tubes.

FRANK ELLISON BEST.
